UNITED STATES PATENT OFFICE.

JOHN R. SCOHY, OF OKMULGEE, OKLAHOMA.

GLASS-CYLINDER CUTTER.

1,420,867.

Specification of Letters Patent. Patented June 27, 1922.

Application filed January 19, 1920. Serial No. 352,486.

To all whom it may concern:

Be it known that I, JOHN R. SCOHY, a citizen of the United States, and a resident of Okmulgee, in the county of Okmulgee,

5 and State of Oklahoma, have invented a certain new and useful Glass-Cylinder Cutter; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 My invention has for its object to provide a cutter for cutting glass cylinders. Such cylinders are formed in the manufacture of window glass and other glass articles. The cylinders are cut into suitable lengths for 20 the purpose of flattening. My invention provides a means whereby two or three cutters may be used and operated by one operator. Each cutter has a high resistance wire which is heated by an electric current and 25 means is provided whereby the wire may be readily placed in position and its tension maintained to keep it in contact throughout its length with the glass cylinder notwithstanding its expansion. Also means is provided 30 for readily placing, removing and supporting a plurality of cutters.

The invention may be contained in structures of different forms. To illustrate a practical application of my invention I have 35 selected one of such structures and shall describe it hereinafter. The structure selected is illustrated in the accompanying drawings.

Figure 1 is a side view of the cutter and an end view of its supporting means. Fig. 40 2 is an enlarged side view of the cutter. Fig. 3 illustrates an edge view of a wire clamp. Fig. 4 is a top view of the cutter.

1 is a cradle on which the glass cylinders, which are of any suitable length, are laid. 45 The cylinders may be cut into any desired number of parts. In the construction shown the cradle 1 is provided with an extension 2 having a pair of bars 3 that form a suitable supporting track. A frame 4 is supported on the bars 3 by suitable flanged wheels 5. The frame 4 is connected to and supports the cutter. This provides a means whereby any number of cutters may be shifted to any point or points along the 50 cylinder as any number of frames 4 may be placed on the track and thus shifted to any

desired position and operation of the cutters started as fast as they may be placed so that any number of cutters may be operating at the same time.

60 The frames 4 are provided with arms 6 which are pivoted to the frames. The arms 6 are of a length sufficient that when they are turned down to substantially horizontal position they will extend over the cradle 1 and particularly over the top of the cylinder 65 7 placed in the cradle. A spring 8 may be connected to each arm 6 and to a bracket 9 in such a way as to be swung below the pivot of the arm 6 when the arm 6 is down 70 and above the pivot when the arm 6 is up. The spring 8 thus operates to hold the cutter down against the glass cylinder 7, whatever may be the diameter of the glass cylinder, within of course certain limitations, and 75 also to hold the arm 6 up out of the way when the arm 6 is raised so as to cause the spring 8 to pass the pivot of the arm 6. In order to limit the backward movement of the arm 6 that would otherwise be caused 80 by the operation of the spring 8, the arm 6 may be provided with a suitable stop, such as the stop 10, that may engage with the bracket 9 and thus hold the arm 6, through 85 the operation of the spring 8, in an upright position.

The cutter 11 is connected to the arm 6 by means of the sleeve 12 which surrounds the arm 6 and is slidably adjustable along the arm 6 to bring the cutter over the axes 90 of the cylinders notwithstanding any variations of diameter of the cylinders. If desired, the sleeve 12 may be locked to the arm 6 by any suitable means.

95 The sleeve 12 is provided with ears 13 between which may be placed the ear 14 located on the cutter 11 and thus the cutter 11 is pivotally connected to the sleeve 12 by means of the pin 15.

The cutter 11 is provided with insulating 100 blocks 16 which are secured to a plate 17 to which the ear 14 is connected. The electrodes or terminals 18 and 19 are secured to the insulating block 16 by means of the pins 20. A movable insulating plate 21 is located on the pins 20. The plate 21 is provided with slots 22 through which the pins extend. The blocks 16 are located on opposite sides of the plate 21 and one at each end of the plate 21 while the electrodes 18 105 and 19 extend in opposite directions and are also located on opposite sides of the plate 21.

The edge 35 of the plate 21 may be shaped so as to conform with the contour of the objects to be cut. In the particular example illustrated, the edge 35 is curved so as to 5 make it conform substantially to the curvature of the cylinders of glass that are cut by the cutting device. A wire 23 having suitable resistance is connected to the cutter by means of a pin 24 that is located on one of 10 the blocks 16. The wire 23 extends from the pin 24 underneath the electrode 18. The pin 24 is so located with respect to the electrode 18 that when the wire 23 is passed around the cylinder the wire will make contact with the electrode 18. When the wire 15 23 is placed on the cylinder it extends beneath one of the blocks 16 and passes around the cylinder to the wheel 25. The wheel 25 is preferably a flanged wheel so as to hold 20 the wire in place. The wheel 25 is so positioned with respect to the electrode 19 that the wire 23 in extending from the surface of the cylinder to the wheel 25 will make good contact with the electrode 19. Inasmuch as the pin 24 and the wheel 25 are so 25 located with respect to the electrodes 18 and 19 that they press the wire against the electrodes, the moment that the cylinder is separated into its parts by the heat of the wire, 30 the wire separates itself from the electrodes and thus the circuit through the wire is automatically opened.

Means is provided for keeping the wire under tension. The end of the wire is secured to a block 26. The block 26 may be provided with a suitable clamp consisting of the pivoted member 27 which is pivoted to the ear 28 formed on the block 26. The wire may be clamped between the arm or 40 pivoted member 27 by means of the threaded angular rod 29. By rotation of the rod 29 in one direction the arm 27 will clamp the wire 23 at any suitable point near its end.

The block 26 is slidably supported on a 45 U-bar 30 which is secured to the cutter 11, such as to one of the blocks 16. The block 26 is provided with openings in which the U-bar 30 is located and thus the block 26 may be shifted along the U-bar 30. A spring 50 31 is connected to the block 26 by any suitable means and to the end of the U-bar 30. The spring 31 operates to pull the block 26 towards the outer end of the U-bar and in so doing keeps the wire 23 under tension and 55 thus takes up any slack that might be caused by expansion of the wire and keeps the wire 23 in contact with the glass cylinder and the electrodes.

The plate 21 is by this arrangement located not only between the electrodes 18 and 60 19 but also between the portions of the wire near the ends and intermediate the electrodes. The plate 21 is yieldably pressed against the cylinder 7 by means of the spring 65 32. The pulling of the spring 31 on the

wire thus indirectly operates to compress the spring 32 more or less by pulling with a relatively slight degree the plate 21 against the surface of the glass cylinder. The plate 21 prevents contact between the 70 portions of the wire and consequent short circuiting between the portions of the wire located in the vicinity of the electrodes.

Suitable connection is made between the electrodes and the source of current supply. 75 If desired, the connections may extend through the arm 6, to the frame 4, on which may be located a suitable switch 33 for completing the circuit of the wire 23 with a source of current supply. 80

I claim:

1. In a glass cutting means, a track, a frame movable along the track, an arm pivoted to the frame, a cylinder cradle, a glass cutter supported on the arm, and a spring 85 for delivering the arm towards the cradle and for holding the arm in a vertical position away from the cradle.

2. In a glass cutter, a pair of electrodes, insulating blocks for supporting the electrodes, a resistance wire for surrounding objects to be cut, means for anchoring one end of the wire and drawing the other end of the wire so as to press the wire against the electrodes and the object to be cut, and a 95 plate having an edge conforming substantially to the shape of the object and located intermediate the electrodes and their supporting blocks and overlapping portions of the wire located between the electrodes. 100

3. In a glass cutter, a supporting frame, a pair of electrodes located at the ends of the supporting frame, a resistance wire extending around the object to be cut and to the electrodes, and having overlapping portions 105 located between the electrodes, a movable insulating plate located between the electrodes and between the overlapping portions of the wire between the electrodes.

4. In a glass cutter, a supporting frame, a pair of electrodes located at the ends of the supporting frame, a resistance wire extending around the object to be cut and to the electrodes, and having overlapping portions located between the electrodes, a shiftable 115 insulating plate located between the overlapping portions of the wire and movable between the electrodes.

5. In a glass cutter, a supporting frame, a pair of electrodes located at the ends of the supporting frame, a resistance wire extending around the object to be cut and to the electrodes, and having overlapping portions located between the electrodes, an insulating plate located between the overlapping 125 portions of the wire and movable between the electrodes, a spring for pressing the insulating plate towards the glass, the plate being located between the overlapping portions of the wire between the electrodes. 130

6. In a glass cutter, a supporting frame, a pair of electrodes located at the ends of the supporting frame, a resistance wire extending around the object to be cut and to 5 the electrodes, and having overlapping portions located between the electrodes, an insulating plate located between the overlapping portions of the wire and movable between the electrodes, a spring for pressing

the insulating plate towards the glass, the 10 plate being located between the overlapping portions of the wire between the electrodes, means for keeping the wire under tension and in contact with the object to be cut and the electrodes. 15

In testimony whereof I have hereunto signed my name to this specification.

JOHN R. SCOHY.
